US00D409239S

United States Patent

[19]

Kollath et al.Patent Number: Des. 409,239*Date of Patent:  May 4, 1999*[54] SET OF PLAY MONEY OF VARIOUS DENOMINATIONS*[76] Inventors: Richard Craig Kollath, 12336 Rollingwood Ct., Gulfport, Miss. 39503; Richard Lee Huffman, 520 Beach Blvd. #501, Biloxi, Miss. 39530*[] Term: 14 Years*[21] Appl. No.: 29/064,619*[22] Filed: Jan. 7, 1997*[51] LOC (6) Cl. .... 19-08*[52] U.S. Cl. .... D19/11; D19/9*[58] Field of Search .... D19/11; D21/376, D21/383-385; 283/57, 70, 94; 235/381; 273/243, 288, 292, 148 R, 459*[56] References Cited*U.S. PATENT DOCUMENTS

D. 28,782 6/1898 Grant D19/11

D. 47,031	3/1915	De La Garza	D19/11
D. 83,911	4/1931	Patch et al.	D19/11
D. 173,394	11/1954	Shore	D19/11
D. 397,145	8/1998	Morozov	D19/11
477,038	6/1892	Wood	283/57
1,692,405	11/1928	Freeman	283/94
4,139,219	2/1979	Herndon	283/57
5,442,162	8/1995	Armel	235/381
5,533,759	7/1996	Jeffers	283/70

Primary Examiner—Martie K. Holtje[57] CLAIM*The ornamental design for a set of play money of various denominations, as shown and described.*DESCRIPTION*FIG. 1 is a front elevational view of a set of play money of various denominations showing our new design. The rear thereof is plain and unornamented and the articles are of conventional thickness.*1 Claim, 1 Drawing SheetFig. 1